UNITED STATES PATENT OFFICE

HERBERT H. DOW, OF MIDLAND, MICHIGAN, ASSIGNOR TO THE DOW CHEMICAL COMPANY, OF MIDLAND, MICHIGAN, A CORPORATION OF MICHIGAN

METHOD OF STABILIZING SHIPS

Application filed September 4, 1928. Serial No. 303,708.

The present improvement has regard to a method for reducing the roll of a ship and has more particular regard to a method of reducing the roll of a propeller-driven ship.

5 The object of the invention is to provide a method that will accomplish the stated result without requiring the expenditure of excessive energy and that may be made to operate automatically, i. e., be brought into 10 action by initial rolling movement of the vessel itself. It will, of course, be understood that a stabilizing method of the character in hand may be employed upon any 15 vehicle having a propeller drive and the equivalent of a buoyant support.

To the accomplishment of the foregoing and related ends, the invention, then, consists of the steps and means hereinafter fully described and particularly pointed out in the 20 claims, the annexed drawings and the following description setting forth in detail certain means and one mode of carrying out the invention, such disclosed means and mode illustrating, however, but one of various ways 25 in which the principle of the invention may be used.

Figure 1 represents in plan a steam-driven vessel outlined by the broken line S. A propeller is shown at P, driven by the engine E, 30 steam being derived from the boilers B.

Figure 2 indicates to a larger scale a stern view of such a boat S with propeller P.

It is well known that a buoyantly supported vehicle, such as a ship in water, rolls 35 to port, then to starboard, back to port and so on indefinitely, with a pendulum-like motion, i. e., it exhibits a periodic roll. The forces tending to produce this rolling movement may not be very great relative to the weight 40 of the ship or the forces employed in driving the ship on its way, but the application is rhythmic and the pendulum-like swing or roll of the boat is built up gradually to large proportions by the persistent and repeated 45 rhythmic application of the said relatively small forces. The present invention is designed to utilize forces developed by the ship's engine or motor to resist or neutralize the forces that thus tend to produce the roll 50 of a ship.

It will be noted that incidentally to producing, by means of a screw propeller, the axial thrust which propels the boat through the water or other medium in which it is floating, a turning moment or torque is first developed; that is, the engine which is fixedly mounted in the ship transmits to the propeller (or propellers where more than one is employed) its turning moment. To increase the rate of revolution of the propeller, increased turning moment or torque is required and this turning moment or torque may therefore be varied by varying the rate of revolution of the propeller. The reaction upon the ship of this turning moment is to cause the ship 55 to list or roll slightly in a direction opposite to that in which the propeller is being turned and if the rate of revolution be varied the torque or turning moment will vary and the tendency of the reaction upon the ship to 60 list it will vary accordingly.

If two similar propellers are used and are driven in opposite directions at equal speeds and are respectively made right and left hand, then the turning moments or torques 75 developed by such propellers will be equal and opposite and will be neutralized one by the other so long as the moments remain equal. If, however, the relative speeds of the two propellers be varied, the difference 80 between the altered moments of the port and starboard propellers which now are no longer equal may be made to act at will toward port or towards starboard and to tend to list the ship accordingly.

85 Since action and reaction are equal and opposite in direction it follows that halving the torque will also halve its reaction upon the ship, and doubling the torque will double its reaction upon the ship. It follows, 90 further, that given a ship floating in quiet water unacted upon by outside forces, the ship may be made to roll rhythmically with a pendulum-like action by varying the rate of revolution of her propeller or propellers 95 in step with the natural period of oscillation of the ship.

Based on the foregoing, I have discovered that by varying the moment of torque delivered by the ship to the water through the 100

propeller or propellers in such a way as to augment that torque when such augmentation will resist the forces tending to roll the ship and to decrease that torque when such torque is assisting the forces tending to roll the ship, the rolling may be measurably reduced or prevented. With a single propeller the rate of revolution and turning moment of the propeller will be increased when the ship tends to roll with the direction of revolution of the propeller and will be decreased for the opposite condition. With two propellers having opposing turning moments, the same result is accomplished by increasing the speed and resultant torque of that propeller turning in the direction in which the ship tends to roll and reducing the speed and resultant torque of those propellers turning in a direction opposite to that in which the ship tends to roll. It will be understood that such changes in rate of rotation of the propeller may be applied to one or all propellers whether single or plural to vary the rate of rotation within suitable limits rhythmically in step with the natural period of oscillation of the ship thus bringing into play changes in the torque between ship and water which changes will either act to resist the forces tending momentarily to roll the ship or will reduce the tendency of the ship to roll by reason of the torque developed through its propeller or propellers when the outside forces act therewith.

In its simplest application the rate of revolution of the engine E in Figure 1 will be controlled by varying the steam delivered to it through the valve V by opening and closing same to such an extent in rhythmic consonance with the tendency to roll that the engine speed will rise and fall with that tendency causing the torque developed between the ship and the water and its reaction upon the ship to rise and fall in like manner. Such control may be manual or automatic. One form of automatical control would involve suitable mechanical or electrical connections and actuating devices between a gyroscopic rotor suitably mounted in the ship and the valve V. It is known that a gyroscopic compass may be connected with the steering gear of a ship in a similar manner to maintain same on her course.

Such an application of automatic control is indicated in Figure 1 wherein X represents a gyroscopic rotor connected electrically or mechanically by the dotted lines to the actuating device Y in turn connected with the valve V. The action of such a device will be to automatically open or close the valve V in consonance with the roll of the ship which opening and closing action may be made controllable and adjustable as to extent in any suitable way.

I am aware that in British patent to Forbes, No. 26,827 of 1908, a method of

balancing an airplane having two propellers was proposed. Forbes discloses a heavier than air craft fitted with two propellers driven by a single motor through a common drive shaft and differential gear. By means of brakes applied to the individual propeller drives, either could be retarded thereby causing the other to accelerate in a like degree.

There is a distinct difference in the problems attacked by Forbes and by my invention. A heavier than air airplane is in unstable equilibrium and only supported while in motion and is subject to complete overturning unless balancing forces are properly applied. A ship or other craft supported buoyantly, as by floating in water, is in stable equilibrium but is subject to periodic oscillation or roll. Forbes' device is applied to the balancing of unstably supported airplanes. My invention is applied to preventing or moderating periodic oscillation or roll of buoyantly supported craft. Forbes does indeed balance the airplane by means of the forces brought about by accelerating and retarding propellers. He does not, however, disclose what forces are thus brought into use. It may be readily inferred, however, that since he illustrates propellers set at a considerable angle with the line of forward travel of the craft, he relies upon the vertical component of the propeller pull in the inclined direction which vertical component will be increased with the rate of revolution of the propeller and decreased as such rate is decreased. By accelerating a propeller on that side of the airplane which is depressed and retarding that upon the side which is elevated, the lifting components of the two propellers are changed to increase that upon the depressed side and decrease that upon the elevated side.

But, however, in whatever manner it may be conceived that his invention functions, his problem was to prevent overturning of an unstable heavier than air ship in air and was not concerned with preventing or moderating a natural periodic oscillation or roll of a buoyantly supported craft such as a ship floating in water.

The present invention is distinguished therefrom not only in the problem to be solved but in other respects. Power is not absorbed by my method as by brake resistance. I vary the power input to the driving engine or other motor to effect a change in torque reaction upon the ship through change in the torque transmitted without adding power losses. Forbes requires two propellers located upon opposite sides of the craft, preferably, at considerable distance to either side of the center line so as to increase the lifting moment of the vertical component of the propeller pull. He does not disclose balancing with a single propeller located on the center line or in any other position. My

invention will function by varying the speed of a single propeller located on the center line of oscillation or above or below that line or to either side of it. My invention will further function by varying the speed of one or more of a plurality of propellers and no reliance is placed upon a lifting component of the driving forces developed. Although for securing automatic stabilization I prefer to employ mechanical means to effect speed variations, yet my invention may be applied to the existing craft which are already provided with means for stopping or starting the engine or other driving motor or to vary the speed thereof by operating said means by hand without the installation of further devices.

This application is a division in part of my application Serial No. 228,852, filed October 26, 1927.

Other modes of applying the principle of my invention may be employed instead of the one explained, changes being made as regards the means and the steps herein disclosed, provided those stated by one of the following claims or their equivalent be employed.

I, therefore, particularly point out and distinctly claim as my invention:—

1. In a method of reducing the roll of a propeller-driven water-borne ship subject to periodic roll and having a propeller revolving upon an axis substantially parallel with the axis of such roll, the step which consists in automatically varying the rate of revolution of the power unit driving such propeller in harmonic step with such periodic roll.

2. In a method of reducing the roll of a propeller-driven water-borne ship subject to periodic roll and having a propeller revolving upon an axis substantially parallel with the axis of such roll, the step which consists in automatically varying the rate of revolution of the power unit driving such propeller in harmonic step with the initial stage of such periodic roll.

3. In a method of reducing the roll of a propeller-driven water-borne ship subject to periodic roll and having a propeller revolving upon an axis substantially parallel with the axis of such roll, the step which consists in automatically increasing the torque delivered to such propeller when the ship tends to roll in the direction of rotation, and automatically decreasing such torque when the ship tends to roll counter to the direction of rotation of such propeller.

4. In a method of reducing the roll of a propeller-driven water-borne ship subject to periodic roll and having at least one independently driven propeller revolving upon an axis substantially parallel to the axis of roll of the ship, the step which consists in automatically varying the rate of revolution of such propeller as the ship rolls so as to

vary the torque reaction of the propeller upon the ship with the rolling action thereof.

5. In a method of reducing the roll of a propeller-driven water-borne ship subject to periodic roll and having at least one independently driven propeller revolving upon an axis substantially parallel to the axis of roll of the ship, the steps which consist in automatically increasing the rate of revolution of such propeller as the ship rolls so as to vary the torque reaction of the propeller upon the ship with the rolling action thereof, and automatically decreasing the rate of revolution when the ship tends to roll counterwise.

6. The method of converting a propeller-driven water-borne ship having a power unit directly connected with the propeller, said ship being subject to a tendency to periodic roll, into a such ship less subject thereto, which consists in employing existing means adapted to change the rate of revolution of said power drive and propeller to vary the rate of revolution thereof in harmonic step with the said tendency to periodic roll.

7. The method of converting a propeller-driven water-borne ship subject to a tendency to periodic roll into a such ship less subject thereto, which consists in adding to existing means adapted to change the rate of revolution of a power unit driving said propeller, means to automatically vary the said rate of revolution of said power unit in harmonic step with the said tendency to periodic roll.

8. The method of converting a propeller-driven water-borne ship subject to a tendency to periodic roll into a such ship less subject thereto, which consists in adding to existing means adapted to change the rate of revolution of a power unit driving said propeller, means to automatically vary the said rate of revolution of said power unit in harmonic step with the said tendency to periodic roll, said added means being adapted to automatically cause said existing means to change the rate of revolution of the power unit and propeller in response to a roll of the ship in its initial stage.

Signed this 9th day of June, 1928.
